UNITED STATES PATENT OFFICE.

CHARLES A. KING, OF MERIDEN, CONNECTICUT.

BREECH-LOADING FIRE-ARM.

SPECIFICATION forming part of Letters Patent No. 356,321, dated January 18, 1887.

Application filed August 30, 1886. Serial No. 212,141. (No model.)

To all whom it may concern:

Be it known that I, CHARLES A. KING, of Meriden, in the county of New Haven and State of Connecticut, have invented new improvements in Breech-Loading Fire-Arms; and I do hereby declare the following, when taken in connection with accompanying drawings and the letters of reference marked thereon, to be a full, clear, and exact description of the same, and which said drawings constitute part of this specification, and represent, in—

Figure 1, a longitudinal sectional side view showing the barrel in the closed position; Fig. 2, the same view as Fig. 1, showing the parts in the position of the barrel open; Fig. 3, a detached view showing the connection between the barrels and slide; Fig. 4, a top view of the frame, the barrels removed.

This invention relates to an improvement in that class of fire-arms in which the barrels are hung to the frame forward of the recoil-plate, and so that the rear end of the barrel tips up to open the cartridge-chamber, and known as "barrel tilting up at the breech," and with special reference to the class known as "concealed hammer"—that is, in which the hammer is arranged entirely within the receiver and brought to the cocked position in the opening movement of the barrel, this class of arms being usually double-barrel, and in this class of arms the mainspring by which the hammer is operated is usually of flat leaf or V spring character.

The object of my invention is the employment of helical springs arranged in the frame forward of the hammers, and a device between the barrels and the mainsprings to relieve the hammers from a portion of the power of the mainsprings as the barrels are opened, and also a simple mechanism between the barrels and hammers, whereby the hammers are thrown to the cocked position in the opening of the barrels.

A represents the frame, which extends rearward to form the recoil-plate B, from which the tangs C extend to secure the frame to the stock in the usual manner. To the forward end of the frame A the forearm D is hinged upon a pintle, E, and to the forearm the barrels F are fixed in the usual manner. Beneath the barrels, at the rear end, is a lug, G, which enters a recess in the frame, and which is con-

structed with a notch or shoulder, H, into which a bolt, I, enters to lock the barrels in the closed position, the bolt being operated by a lever, J, on the upper side of the tang C, through an eccentric, K, and lever L, to which the said bolt is hung, this being a common and well-known arrangement of locking device, the parts being shown in broken lines in the locked position, Fig. 1, and in the unlocked position, Fig. 2.

A hammer, M, is hung upon a pivot, a, in the frame beneath the rear end of each barrel, and in such relation to the barrels that the nose of the hammers b may strike the primers on the cartridges when the hammers are thrown forward. Below the hammers and in the frame is a longitudinally-guided slide, N. The slide extends to the rear of the pivot upon which the hammers are hung, and is there provided with upwardly-projecting studs or shoulders d. On each of the hammers is a corresponding stud or shoulder, e, forward of the studs d, but below the pivot upon which the hammers are hung, and so that as the slide N is drawn forward, as from the position in Fig. 1 to that in Fig. 2, the studs d, bearing against the studs on the hammers, will draw the hammers from the position seen in Fig. 1 to the cocked position seen in Fig. 2.

In the frame forward of the hammers a two-armed or bell-crank lever, f g, is hung upon a fulcrum, h. (See Fig. 3.) The one arm, g, is connected to the forward end of the slide N. The other arm, f, is engaged by a link, i, hung to the barrels upon a pivot, l, and so that as the barrels are raised from the position seen in Fig. 1 to that seen in Fig. 2 the consequent turning of the lever f g draws the slide N forward, and brings the hammers to the full-cock position, as seen in Fig. 2, at which time the noses of the sears P engage the full-cock notch R on the hammers, as seen in Fig. 2, from which the hammers can be released by pulling the triggers S in the usual manner.

Upon the return of the barrels to the positions seen in Figs. 1 and 3 the slide is moved rearward to take the studs d so far to the rear of the studs e on the hammers that they may not interfere with the movement of the hammers in imparting the blow; but until the barrels are brought to substantially their

closed position the studs *d* will so stand in the path of the studs *e* as to interrupt the striking movement of the hammers, should they be released before the barrels are closed.

5 In the frame forward of the hammers the spring-chambers *T* are formed. These chambers are simply round holes drilled into the frame from the hammer-chamber forward, the axis of the chambers being in a line at substantially right angles to and below the axis of the respective hammers. In the rear end of each spring-chamber a follower, *U*, is arranged to bear against the respective hammers forward of and below the pivot *a*, and at the bearing-point, preferably, anti-friction rolls *W* are arranged, against which the followers may bear. The mainsprings *V* are helical springs of sufficient strength, one end bearing against the forward end of the follower *U* and the other end supported in the chambers forward, and so that as the hammers are turned to the cocked position in opening the barrels the hammers below the pivot bear against the followers and act as cams thereon to force the followers forward and away from the hammers to compress the springs, as seen in Fig. 2.

In each spring-chamber forward of the springs, and so as to form bearings upon which that end of the springs may rest, a piston, *m*, is arranged, and so as to work freely therein. From each piston *m* a spindle, *n*, extends through that end of the spring-chamber forward, the spindles terminating in a cam-shaped end, *r*—that is, the end is eccentric to the axis upon which the barrels turn. This eccentric or cam-shaped end stands in the path of a roller, *s*, or other suitable bearing-point arranged in the forearm so as to work over the cam-shaped forward end of the spindles as the barrels are opened and closed.

The cam shape of the forward end of the spindles is downward and backward, as seen in Fig. 1, and in that position the length of the spindles is such, as shown, that the bearing 45 of the forearm upon the spindles will force the pistons *m* against and so as to compress the respective springs to some extent. Then as the barrels are opened the rollers or bearings on the forearm move downward over the 50 cam-shaped ends *r* of the spindles, which permits the spindles and pistons to move forward, as seen in Fig. 2, and thereby reduce the pressure of the springs to the extent that the pistons are moved, so that in the opening movement of the barrels the power of the springs is reduced, thus relieving the resistance to the opening movement of the hammers to the extent that such power of the springs is reduced. On the return or in the closing movement 55 of the barrels the bearings on the forearm work against the forward ends of the spindles, and force the pistons inward to compress the mainsprings, and so that as the barrels are finally closed the mainsprings have regained their full power. By thus reducing the power of the mainsprings as the barrels are opened the hammers offer a diminishing

resistance to the opening of the barrel, and the hammers and the working parts being so relieved from the force of the mainsprings the wear upon the parts is correspondingly reduced.

In detaching the barrels it is necessary to make a disconnection between the slide *N* and the barrels. To this end I construct the link *i* with a thumb-piece, *s'*, which stands in a recess, *t*, in the under side of the frame when the barrels are in the closed position, and the link is constructed with a notch, *u*, upon its rear side to set over the pivot or trunnion on the arm *f*, as seen in Fig. 3, and so as to engage with the arm for operation; but when desired to disengage the barrels the link *i* is readily turned forward by applying the thumb to the thumb-piece *s'*, as indicated in broken lines, Fig. 3, so as to disengage the link from the arm *f* and leave the barrels free to be removed. Then, in replacing the barrels when set in place, the link *i* is again turned into connection with the arm *f*.

As a protection against accidental discharge of the hammers I arrange a dog, *w*, over the triggers, which may be turned by means of a slide, *v*, on the tang to a position over the triggers, as seen in Fig. 2, to prevent their being pulled or thrown from that position to the position seen in Fig. 1, to leave the trigger free. This mechanism for mechanically bringing the dog to the locked or unlocked position is a common and well-known device; but to make this same dog act automatically, so that as the barrels are thrown open it will be brought into the stopping position, I hang the upper end of the lever *L* in a recess, *2*, above the connection between the lever *L* and the eccentric, and so that the recess *2* serves as a fulcrum upon which the lever *L* may swing backward and forward, as from the position seen in Fig. 1 to that in Fig. 2, and return.

The connection between the eccentric and the lever is a slide, *3*, arranged to work in a plane at right angles to the axis of the eccentric, the eccentric taking a bearing in the slide, so as to move it backward and forward, and the lever *L* extending through a slot in the slide *3*, and there connected with the slide by a pin, *4*, so that the movement of the slide backward or forward is imparted to the lever *L*. From the rear end of the slide a rod, *5*, extends to a point near the dog *w*, so that it may bear above the pivot *6*, on which the dog is hung; hence, as the slide *3* is moved rearward in opening the barrels, the rod *5* moves rearward accordingly, and strikes the dog above the pivot, throwing the dog from the position seen in Fig. 1 to that seen in Fig. 2, and as this rear movement of the slide must occur before the barrels are opened, it follows that the triggers will be locked before the opening movement of the barrels commences, and the dog will remain in that condition until the barrels are returned to place and properly locked, for until the slide *3* is forced forward, taking with it the bolt into its locked position, the bar 5

will still retain its position against the dog to prevent its being interlocked, and after the barrels are properly locked the operator will move the slide *v* and throw the dog to the unlocked position, as seen in Fig. 1, where it may remain until the barrels are opened, or until such time as the operator may choose to mechanically relock the triggers.

The arrangement of a helical spring forward of the hammers, and having its axial line below the pivot of the hammer, and adapted to bear upon the hammer below its pivot, is applicable to other classes of arms.

While the invention is designed and illustrated as applied to a double-barrel arm, it will be apparent that the invention is alike applicable to single-loaders. I therefore do not wish to be understood as necessarily limiting the invention to a double-barrel gun.

20 I claim—

1. In a breech-loading fire-arm in which the barrel is hung forward to be tilted up at the breech in opening, the combination therewith of a hammer hung in the frame at the rear of the barrel, a longitudinal slide arranged in the frame below the pivot of the hammer, a projection on the said slide adapted to engage a corresponding point on the hammer below the pivot upon which the hammer is hung, the said slide extending forward beneath the barrel, with a bell-crank lever hung in the frame in rear of the pivot upon which the barrel is hung, one arm of said lever in connection with said slide, and a link between the barrel and the other arm of said lever, substantially as described.

2. In a breech-loading fire-arm in which the barrel is hung forward to be tilted up at the breech in opening, the combination therewith of the hammer *M*, hung below the barrel and provided with a stud, *e*, below its pivot, a longitudinal slide, *N*, arranged in the frame below the hammer, said slide provided with a stud, *d*, corresponding to the stud *e* in the hammer, the said slide extending forward beneath the barrel, a bell-crank lever, *f* *g*, hung in the frame in rear of the pivot upon which the barrel is hung, one arm, *g*, in connection with said slide *N*, a link, *i*, hung to the barrel, constructed with a notch, *u*, adapted to engage a corresponding trunnion on the arm *f* of the said lever, and the said link also

constructed with a downward thumb-piece, *s*, extending into a corresponding recess upon the under side of the frame, substantially as 55 and for the purpose described.

3. In a breech-loading fire-arm in which the barrel is hung forward to be tilted up at the breech in opening, the combination therewith of a hammer hung at the rear below the barrel, a spring-chamber, *T*, in the frame forward of the hammer, the axis of the chamber being below the axis upon which the hammer turns and at right angles thereto, a follower, *U*, in said spring-chamber and adapted to 60 bear upon the hammer below its pivot, a piston, *m*, arranged in the forward end of said chamber, a helical spring, *V*, between said piston and follower, the said piston constructed with a spindle extending forward therefrom, 65 the said spindle terminating in a cam shape at its forward end, with a corresponding bearing upon the forearm to work against the said cam-shaped end of said spindle, substantially as described.

4. In a breech-loading fire-arm in which the barrel is hung forward to be tilted up at the breech in opening, the combination therewith of a bolt longitudinally arranged in the frame at the rear and adapted to engage a corresponding notch at the rear end of the barrel when the barrel is in the closed position, the said bolt movable backward and forward, mechanism, substantially such as described, 80 for imparting backward and forward movement to said bolt, a hammer hung in the frame at the rear below the barrel, mechanism, substantially such as described, between the hammer and the barrel, whereby the hammer is thrown to the cocked position as the barrel is 85 opened, a sear adapted to engage said hammer in the cocked position, a trigger arranged to disengage said sear, a dog, *w*, hung in the frame above the trigger, and so as to swing over the trigger to serve as a stop therefor, or 90 turned therefrom to leave the trigger free, a rod, *5*, extending rearward from the bolt mechanism into the path of said dog, substantially 95 as and for the purpose described:

CHARLES A. KING.
